UNITED STATES PATENT OFFICE.

PHILIP K. WILLIAMS, OF GLASTONBURY, CONNECTICUT, ASSIGNOR TO THE J. B. WILLIAMS COMPANY, OF GLASTONBURY, CONNECTICUT, A CORPORATION OF CONNECTICUT.

SOAP CAKE.

1,267,949.

Specification of Letters Patent. Patented May 28, 1918.

Application filed April 5, 1917. Serial No. 160,066.

To all whom it may concern:

Be it known that I, PHILIP K. WILLIAMS, a citizen of the United States, residing at Glastonbury, in the county of 5 Hartford and State of Connecticut, have invented new and useful Improvements in Soap Cakes, of which the following is a specification.

My invention relates to the class of articles above named, and an object of my invention, among others, is to provide means for securing an inserted piece within a cake of soap in a sightly and efficient manner and without any liability of the insert becoming loose.

One form of soap cake embodying my invention and in the making and use of which the objects herein set out, as well as others, may be attained, is illustrated in the 10 accompanying drawings in which—

Figure 1 is a face view of a cake of soap embodying my invention.

Fig. 2 is a view in section through the cake on plane denoted by dotted line 2—2 15 of Fig. 1, and showing the body tightly embracing the insert.

Fig. 3 is a similar view but showing the relative size (exaggerated) of the insert and body at the time they are placed together.

My invention is especially applicable in the production of an ornamental soap cake, the ornament being in the nature of an inserted piece of soap of a character different from that of the main part of the cake, one difference in characteristic being in 20 color so that the outline of the insert may be readily distinguished.

In carrying my invention into effect I 25 produce a cake 3 of soap of one color making a recess 4 therein in which the insert 5 of a different color is placed. Preferably the insert is located in a recess, that is, an opening extending only partially through 30 the cake, but this feature is not absolutely essential to the embodiment of my invention.

In order to securely hold the insert in place in the recess I so manipulate the mass 35 comprising the cake and that comprising the insert that the former will close about and squeeze the insert so that it will be tightly held. In a satisfactory method of

forming the cake of soap and embodying my invention the material to comprise the 40 main part of the cake is provided with a certain amount of moisture, as water, and the material comprising the insert is provided with a considerably less amount of moisture as water. A cake of soap is 45 formed to the proper shape from the mass containing the greater amount of moisture and of a certain color, the recess 4 being formed in this mass. The insert 5 of contrasting color is formed to proper shape to 50 fit the recess in the other mass of soap containing the greater amount of moisture. As herein shown this insert is in the form of an animal which is placed in the recess in the cake, and the whole is then subjected 55 to a certain amount of pressure in forming dies to compact the mass but not to an extent to distort the shape of the recess or the insert.

After being thus formed the cake is 60 allowed to dry out and harden and in this process the mass comprising the cake will close about the insert, owing to the relatively greater and more rapid shrinkage of the outer cake as compared with the 65 inner piece or insert, and thus tightly grasp it so that it will be securely held in the recess.

The foregoing description applies in cases 70 where the body part and insert are made at substantially the same time, it being the intent of my invention that at the time of completion of the insert and the body part that are to fit together, the last to be formed should contain such amount of moisture as 75 to cause the body part to have the greatest amount, and the parts should be united at this time so that when the insert is placed in the body part the latter will contain the greater amount of moisture.

In accordance with the provisions of the 80 patent statutes, I have described the principles of operation of my invention, together with the soap cake which I now consider to represent the best embodiment thereof; but 85 I desire to have it understood that the cake shown is only illustrative, and that the invention can be carried out by other means.

I claim—

1. A soap cake comprising a body part, 90 and an insert inclosed within the body part,

and both of substantially the same material, said body part having more moisture than the insert.

2. A soap cake comprising a body part, 5 and an insert inclosed within the body part and secured by a contracting action of the body part on the insert.

3. A soap cake comprising a body part, 10 and an insert inclosed within the body part and both of substantially the same material, the insert being secured within the body part by the contracting action of the latter caused by shrinking.

4. The process of securing an insert with- 15 in the body part of a cake of soap, both being of substantially the same material, that consists in forming the body part from a soft mass having a certain amount of moisture and with a recess therein, and

placing in the recess an insert of substan- 20 tially the same material as the body part but having a less degree of moisture.

5. The process of making a soap cake that consists in forming the body of the cake from a mass having a certain degree of 25 moisture and with a recess therein, placing in said recess another soft mass with a less degree of moisture and then permitting the entire cake to dry out whereby the insert is held by the binding action of the body of 30 the cake caused by shrinking.

6. A soap cake comprising a body part and an insert shaped to fit together, the last to be formed containing an amount of moisture to cause the greater amount of moisture 35 to be in the body part.

PHILIP K. WILLIAMS.
